UNITED STATES PATENT OFFICE.

THOMAS J. COOKSON, OF CINCINNATI, OHIO.

STEAM-TRAP.

No. 833,777.

Specification of Letters Patent.

Patented Oct. 23, 1906.

Application filed November 4, 1904. Serial No. 231,453.

To all whom it may concern:

Be it known that I, THOMAS J. COOKSON, a citizen of the United States of America, and a resident of No. 2137 Grand street, in the city of Cincinnati, in the county of Hamilton and State of Ohio, (whose post-office address is No. 323 West Fourth street, in the city of Cincinnati, in the county of Hamilton and State of Ohio,) have invented an Improvement in Steam-Traps; and I do hereby declare the following to be a full and exact description thereof, reference being had to the accompanying drawings, making part of this specification.

15 My invention relates to steam-traps; and it has for its object the improvement in the construction of such devices whereby they are simplified and rendered more efficient in action.

20 The novelty of my invention consists in the combination and subcombination of the parts, as will be hereinafter set forth, and specifically pointed out in the claim.

Figure 1 is a top view of my steam-trap. 25 Fig. 2 is a section on line 2 2 of Fig. 1. Fig. 3 is a section on line 3 3 of Fig. 2. Fig. 4 is a vertical section through a portion of the top of bucket-guide.

In the drawings, A represents the body of 30 the trap, and B the piston-valve. The body of the trap consists of a cylindrical box having a solid bottom b and a removable top b². The top b² is secured by bolts b³ to the body A. At the side of the body, near the top, is a 35 screw-thread opening b⁴ to receive a steam-pipe. Directly opposite to the opening b⁴ is a threaded opening b⁵ to receive the drain-pipe. Within the body A is a bucket C, which is free, so that it can be raised or 40 lowered by the action of the water which will accumulate in the body A. The bucket C is provided with a guide C², which slides up and down in the pipe b⁶, projecting downwardly from the center of the top b². The upper end 45 of the guide C² is provided with a sliding valve-face C³, which closes the hole e, that passes through the stem e², said stem being provided with a valve-seat e⁴ at its lower end. The stem e² extends down from the piston E, 50 that plays in the cylinder F. The piston E has a small opening E² to relieve the pressure of water on the piston E. The pressure can also be relieved by the piston E being made to play loosely in the cylinder F. The cylinder F is attached to the cap b² by the threaded portion f. The cylinder F is also

provided with a cap f², which screws onto the top of the cylinder F, making it perfectly tight. Attached to the lower end of the stem e² is a valve-face e⁴, which closes the lower part of the cylinder F by seating on the valve-seat f³. The top b² has a passage-way b⁸, which leads from the chamber where the bucket C is to the outlet-opening b⁵ through the openings f⁴, which are in the cylinder F. 60 A threaded stem G, provided with a stuffing-box, passes through the top of the cap f². This stem G is for forcing down the piston E at any time, so that the trap can be blown out and emptied should occasion require it. 65 The valve-face C³ is screwed into the sliding piece C⁴, which slides up and down in the sleeve C⁵, it in turn being screwed into the guide C². The object in having C⁴ slide up and down in C² is to prevent valve-face C³ 70 from sticking, which is attained as follows: When the bucket C drops, it falls until the upper part of C² strikes the lower part of C⁴, the blow struck assuring the dropping of the valve-face C³, thereby preventing any sticking of the valve-face C³. 75

The advantage in my trap over other traps of this class is that an immense volume of water can be taken care of without loss of steam, the passage-way between the bucket- 80 chamber and outlet being controlled by the pressure of water.

The operation of my steam-trap is as follows: The water from the condensed steam in the pipes entering the body of the trap 85 through the inlet b⁴ gradually raises the bucket C until the valve-face C³ strikes the valve-seat e³, closing the hole e in the stem e², also forcing the valve-face e⁴ up against the valve-seat f³, thereby closing off all communication between the chamber where the bucket C is and the passage-way b⁸, which leads to the outlet b⁵. As there is no outlet for the water, it will continue to rise in the chamber where the bucket C is and overflow 90 into the bucket C. This will continue until the bucket C becomes heavy enough to sink, when it will open the valve which closes the bottom of the tube e². Water will then flow through the hole e (the pressure of steam 95 forcing it up) to the top of the piston E, which being of a greater area than the valve-face e⁴ will be forced down, permitting the water in the bucket C to flow up through the pipe b⁶, entering at the bottom and passing 100 out through the opening b⁸ to the drain-pipe opening b⁵. When the bucket has become

empty, it will rise, closing the valve between the chamber containing bucket C and the passage-way b^8 .

Having thus explained my invention, what 5 I claim is—

In a steam-trap, the combination of a steam-trap chamber provided with an inlet, a bucket-float within said chamber, a guide for the bucket, a valve-face attached to top 10 of guide so it can move vertically independent of the movement of the guide, a valve-seat, a piston-valve having ends of different

areas, means for passing pressure from small area to large area, means for automatically relieving pressure on large area, outlet for 15 water through same pipe through which bucket-guide passes, means for opening valve from the outside of trap, all substantially as described.

THOMAS J. COOKSON.
